UNITED STATES PATENT OFFICE.

WILLIAM VOGEL, OF CHICAGO, ILLINOIS.

TOY.

SPECIFICATION forming part of Letters Patent No. 308,045, dated November 11, 1884.

Application filed March 20, 1884. (No model.)

To all whom it may concern:

Be it known that I, WILLIAM VOGEL, of Chicago, in the county of Cook and State of Illinois, have invented certain new and useful Improvements in Toys; and I do hereby declare the following to be a full, clear, and exact description of the invention, such as will enable others skilled in the art to which it pertains to make and use it, reference being had to the accompanying drawings, which form part of this specification.

My invention relates to an improvement in toys; and it consists in a rubber or other collapsible ball or body, which has preferably attached to it an operating rod or handle, and which has secured to it, at any suitable point or points, a short metallic tube, to which is applied a perforated cover of any kind, for the purpose of clamping a piece of paper or other similar material between the mouth of the tube and the opening in the cover, as will be more fully described hereinafter.

The object of my invention is to provide a toy whereby children can cause, by compressing the ball or body, the air contained in the body, to burst one or more pieces of paper, and thus make a loud noise or report.

Figure 1 is a side elevation of a toy embodying my invention, having a number of tubes connected to it. Fig. 2 is a vertical section of a body having but a single tube. Fig. 3 is a plan view of the end of the tube, showing the cover turned back. Fig. 4 is a detached view of the cartridge.

A represents a suitable body, which will preferably be made round and of india-rubber, but which may be made of any other shape and of any flexible material. To this body will be preferably attached an operating rod, handle, or lever, B, by means of which the body A will be forced against the ground or other hard substance, for the purpose of flattening the body, and thus causing the air which is compressed within it to burst the paper cartridge. Secured to this body A will be one or more short tubes, C, which will preferably have a rubber packing, D, applied to its outer side, so as to form a tight joint against the paper cartridge. Either pivoted to the tube or detachable therefrom, and which may be applied to the tube like a bayonet-joint, is a suitable cover, G, by means of which the pa-

per can be clamped between the outer end of the neck and the inner side of the cover, and thus be held in position for being burst when the body is flattened by being forced against some hard substance. As here shown, the cover G is pivoted to the tube C, and is provided with a small latch, I, which catches under a projection, J, formed on the tube.

The paper used as a cartridge should be heavy and strong, in proportion to the amount of noise which it is desired to make when the paper is burst. Where only a weak sound or noise is to be made, thin paper—such as is used in newspapers—can be employed; but where it is desired to make a noise like the report of a pistol, heavier and stronger paper will be used.

Ordinarily, the cartridges will consist of small round pieces of paper, which will be packed in a box, ready for use. Where it is desired, a number of these tubes C and covers G may be employed upon the same body, and thus produce more than one explosion at the same time.

In order to operate this toy, the cover G is thrown back, a piece of paper is placed upon the packing D, and then the cover G is returned to position, so as to clamp the paper tightly in place between the mouth of the tube and the opening O in the cover. When the body is forced against some hard substance, the body is made to change its form, and thus compress the air contained in the body. This compressed air breaks or bursts the paper cartridge and causes a loud report. This toy will furnish children all the amusement of the ordinary toy pistol without any of its dangers.

Instead of the lever B, if so preferred, a second compressible ball or body may be attached to the first body, A, by a suitable flexible tube. When the ball or body is suddenly pressed by the hand, the air is forced through the tube into the body, which is provided with a tube and a clamp.

Having thus described my invention, I claim—

1. A compressible body, a tube or pipe connected thereto, and a clamping device for securing the piece of paper in position over the mouth of the tube or pipe, substantially as shown.

2. The combination of a compressible body, a tube, C, connected thereto and provided with a

suitable packing, and a clamping cover, G, for holding the paper against the end of the tube, substantially as described.

3. The combination of the compressible body, a tube, C, connected thereto, a cover for clamping the paper against the end of the tube, and the handle, which is connected to the body, substantially as set forth.

4. The combination of a compressible ball or body having an opening through it to which

the cartridge is to be applied, and a perforated clamping device for holding the paper in position, substantially as specified.

In testimony whereof I affix my signature in presence of two witnesses.

WILLIAM VOGEL.
